UNITED STATES PATENT OFFICE.

THOMAS J. COSTELLO, OF WARREN, OHIO.

CONTINUOUS HEATING-FURNACE.

1,397,367.

Specification of Letters Patent. Patented Nov. 15, 1921.

Application filed October 30, 1920. Serial No. 420,594.

To all whom it may concern:

Be it known that I, THOMAS J. COSTELLO, a citizen of the United States, residing at Warren, in the county of Trumbull and State of Ohio, have invented a new and useful Improvement in Continuous Heating-Furnaces, of which the following is a full, clear, and exact description, reference being had to the accompanying drawings, forming part of this specification, in which—

Figure 1 is a longitudinal vertical section of a heating furnace embodying my invention;

Fig. 2 is a detail sectional view showing one of the supports for one of the water-cooled skids;

Fig. 3 is a horizontal section of a portion of the furnace;

Fig. 4 is a section on the line IV—IV of Fig. 1, and

Fig. 5 is a detail view showing another form of holding links or rods for the skid pipes.

My invention has relation to continuous heating furnaces, and is designed to provide an improved arrangement of the water-cooled skids or bearing pieces upon which the billets or other blanks are moved through the furnace. My improved furnace is particularly designed for use in connection with relatively thin blanks or billets. Heretofore considerable difficulty has been experienced in moving blanks of this character through the furnace under the action of the pusher, by reason of the fact that the blanks tend to buckle upwardly on the skids and override each other. My invention is particularly designed to overcome this difficulty.

The invention will be best understood by reference to the accompanying drawings, in which I have shown the preferred embodiment thereof and which will now be described, it being premised, however, that various changes may be made in the details of construction and arrangement of the several parts, without departing from the spirit and scope of my invention, as defined in the appended claims.

In these drawings, the numeral 2 designates the walls of a continuous heating furnace which is generally of well known type, the products of combustion passing longitudinally through the heating chamber 3 of the furnace from the combustion chamber 4 at the discharge end, and passing out

through one or more stack flues 5 at the opposite ends. The billets or other blanks are pushed through the furnace by the action of any suitable or well known pusher mechanism indicated at 6, forming no part of the present invention.

7 designates the bearing pieces on which the billets are pushed through the furnace, these being preferably in the form of water-cooled skid pipes, water being introduced into said pipes at the downwardly bent end portions 8 thereof at the discharge end. In accordance with my invention, these pipes are given a curvature such that their lowest points are approximately at the middle of the heating chamber, the curvature being preferably substantially gradual and uniform from end to end of their bearing portions. I have found that by reason of this curvature, the billets or other blanks may be pushed therethrough without buckling or overriding, the curvature being effective to overcome this difficulty.

The skids are preferably supported on a plurality of piers 9, which are supported on the bottom of the furnace and which are arranged in longitudinal and transverse rows. Each of these piers is preferably faced at its upper portion with a block or saddle 10 of suitable metal, such as cast iron, and which is formed with a longitudinal semi-circular groove 11 in its upper surface to receive and seat a skid pipe. Means are also preferably provided for positively holding the skid pipes under sufficient tension to maintain substantially their initial curvature. Such means preferably consist of two-piece links or rods 12, which may be welded at their upper ends to the skid pipes and which extend downwardly through the piers and through the floor of the heating chamber into the openings 13 in the base of the furnace. At their lower ends, they are provided with adjustable collars or nuts 14, between which and the washer plates 15 are seated tension springs 16. These tension springs, as will be readily seen, act to hold the skid pipes at all times under sufficient tension to substantially maintain their initial curvature. In this form the rods are shown as made in two pieces, the upper piece having a lower eye which is engaged by a hook on the lower half; so that the upper half may be set in the furnace chamber with the skid pipes and engaged with the lower halves which are inserted from below.

In Fig. 5 I show another preferred form of holding down rods for the skid pipes. In this form the rods are water-cooled, the upper pipe portion 17 being screwed into, or otherwise secured in the skid pipe, while its lower end is screw threaded either internally, or externally, to receive the pipe section 18 forming the lower half of the water-cooled rod. The lower end of the section 18 is preferably peened in to throttle the discharge so that a regulated amount of water will drip therefrom, this water being supplied from the skid pipe circulation. In this form again I show the same adjustable collar or nut 14 screwed on the lower pipe section, and the tension spring 16 seated between the washer plates 15. The flow of water through these hollow water-cooled holding down rods may be regulated by valves, or otherwise, as desired.

The advantages of my invention result from the curved form of the water-cooled skids, whereby buckling and overriding of the blanks is obviated. Also from the provision of means for suitably securing and holding the skids under tension.

I claim:

1. A continuous heating furnace having a skid or bearing piece for the blanks formed with a downward curvature intermediate its end portions, substantially as described.
2. A continuous heating furnace having a water-cooled bearing piece or skid for the blanks to be heated, said piece having a downward curvature intermediate its ends, substantially as described.
3. A continuous heating furnace having a water-cooled bearing piece or skid for the blanks to be heated, said piece having a downward curvature intermediate its ends, together with means for maintaining such curvature, substantially as described.
4. A continuous heating furnace having a skid or bearing piece for the blanks formed with a downward curvature intermediate its end portions, together with means for holding the piece or skid under tension to maintain its curvature, substantially as described.
5. A continuous heating furnace having a skid or bearing piece for the blanks formed with a downward curvature intermediate its end portions, together with members connected to said piece or skid, and springs connected to said members to thereby hold the piece or skid under tension and maintain its curvature, substantially as described.

6. A continuous heating furnace having a plurality of piers or supports on its bottom and formed with grooves in their upper surfaces, and longitudinally extending downwardly curved skids seated and held in such grooves, substantially as described.

7. A continuous heating furnace having a plurality of piers or supports on its bottom and formed with grooves in their upper surfaces, and longitudinally extending downwardly curved skids seated and held in such grooves, together with means for maintaining a downward tension on said skids, substantially as described.

8. A continuous heating furnace having a plurality of supporting piers extending upwardly from the bottom of its heating chamber, said piers having refractory blocks or saddles at their upper ends formed with longitudinally extending grooves, and a plurality of downwardly curved skids seated in said grooves, substantially as described.

9. A continuous heating furnace having a plurality of supporting piers extending upwardly from the bottom of its heating chamber, said piers having refractory blocks or saddles at their upper ends formed with longitudinally extending grooves, and a plurality of downwardly curved skids seated in said grooves, together with means for exerting a downward pull on said skids, substantially as described.

10. A continuous heating furnace having a water-cooled bearing piece or skid pipe and means for exerting a downward tension on the intermediate portions thereof, substantially as described.

11. A continuous heating furnace having a water-cooled bearing piece or skid pipe and means for exerting a downward tension on the intermediate portions thereof, said means being water-cooled, substantially as described.

12. A continuous heating furnace having a skid pipe with intermediate holding-down devices made in a plurality of separable parts, substantially as described.

13. A continuous heating furnace having a skid pipe with intermediate holding-down devices made in a plurality of separable parts, said parts being water-cooled, substantially as described.

In testimony whereof, I have hereunto set my hand.

THOMAS J. COSTELLO.
